United States Patent Office

Des. 210,223

Patented Feb. 20, 1968

210,223

ANTENNA

Aylwin R. Booker, 4887 Palo Drive,
Tarzana, Calif. 91356

Filed Mar. 13, 1967, Ser. No. 6,200

Term of patent 14 years

(Cl. D26—14)

Fig. 1.

Fig. 2.

Fig. 3.

FIGURE 1 is a perspective view of an antenna showing my new design;

FIGURE 2 is a top plan view with some of the rod members in a retracted position; and

FIGURE 3 is a side view thereof.

The dominant features of my design reside in the portions shown in full lines.

I claim:

The ornamental design for an antenna, substantially as shown and described.
